UNITED STATES PATENT OFFICE

HENRY R. TROTTER, OF CHICAGO, ILLINOIS, ASSIGNOR TO HACKER MANUFACTURING CO., OF CHICAGO, ILLINOIS, A CORPORATION OF ILLINOIS

PRINTING PRESS

Application filed April 13, 1932. Serial No. 605,046.

My invention relates to printing presses and particularly to inking mechanism therefor.

It is the purpose of my present invention 5 to provide a printing press wherein the impression cylinder and form carrying bed are relatively reciprocable and which embodies a form inking roller whose circumference is at least equal to the printing length 10 of the bed, so that no portion of the ink distributing surface of the roller will contact with the form twice during a single inking movement of the roller thereover and thus assure full and even distribution of ink on 15 the entire form and the avoidance of pale portions after the first revolution of the small form rollers commonly used.

In addition my invention contemplates a 20 form inking roller of the type heretofore specified which is out of contact with all other rollers while inking a form and which embodies a friction tire at each end engageable with the bed to rotate the roller both before and during its contact with a form, 25 said tires being adjustable radially, so that their surface speed may be maintained equal to the surface speed of the ink carrying portion of the roller; such rotation of the roller independently of its frictional contact with 30 a form serving to avoid slurring of ink either at the edge or intermediate portions of the form.

Furthermore, my invention contemplates the embodiment in the press of means where- 35 by the distribution of ink from the source of supply to the form inking roller is effected after each movement of the form inking roller over a form, whereby two distributions of ink from a freshly inked form inking roller 40 to the form occur prior to each impression taken from the form.

In the drawings chosen to illustrate my invention

Figure 1 is a side elevation of a letter press 45 having my invention incorporated therein;

Figure 2, a view in elevation looking at the right-hand end of Figure 1;

Figure 3, a section on the line 3—3 of Figure 1; and

50 Figure 4, a longitudinal section through

the form inking roller, showing the friction tires at each end of the roller and the means for adjusting them radially so as to maintain the surface speeds of the tires and ink carrying portion of the roller equal.

Referring to the drawings, A indicates the base of the press, said base terminating at its upper end in a table 10, the upper surface of which is formed to provide a trough 11. Slidably mounted in this trough is a form 60 carrying bed 12. At each side of the bed 12 is a longitudinal track 14, and at one side of the right-hand track 14 (Fig. 2) is formed a rack 15 extending longitudinally of the bed. The purpose of the tracks 14 and rack 15 will 65 presently appear. Rising from the sides of the table 10 are metal frame portions 16 and 17 respectively. Journaled in said portions are the trunnions 18 of an impression cylinder 19. The end of the impression cylinder 70 adjacent the portion 17 is provided with a gear 20 which meshes with the rack 15. One of the trunnions 18 is extended through the frame portion 16 and has fixedly thereon an operating handle 21, through the instru- 75

mentality of which latter the impression cylinder 19 may be rotated on its axis in either direction and by reason of the coaction between the gear 20 and rack 15, during such 80 rotation, linear reciprocation of the bed 12 is effected. During reciprocation of the bed from right to left in Figure 1, which reciprocation constitutes the printing stroke of the bed, impression receiving material, such as 85 paper, carried by the cylinder will receive an impression from a suitably linked form carried by the bed. During the opposite or non-printing stroke of the bed the impression cylinder is raised, in this case manually, by a 90 mechanism indicated generally at B, so as to be, during such non-printing stroke, inoperative with respect to a form carried by the bed. When the non-printing stroke of the bed is completed the impression cylinder is 95 again lowered so as to cooperate with a form during the printing stroke of the bed. A suitable paper shelf C is supported on the frame portions 16 and 17 and from which sheets of paper may be manually fed to the 100

impression cylinder 19 as the latter is rotated during the printing stroke of the bed.

At the side of the impression cylinder opposite to the paper shelf C and between the portions 16 and 17 I mount a swinging frame D which comprises a shaft 22 whose ends are journaled in the portions 16 and 17 respectively and fixed on this shaft are arms 23 and 24, the free ends of which constitute journals for the trunnions 25 and 26 respectively, of a form inking roller E in the form of a cylindrical body comprising a tube 27 closed at each end by a head 28, said heads being fixed on an axial shaft 29. Mounted on the exteriorly on the tube 27 at each end of the latter is a ring 30 the outer plane face of which is beveled as at 31. Between the rings 30 the tube 27 is covered with the usual ink receiving composition 32. Mounted on the shaft 29 outwardly of each head 28 is a disk 33 the inner face of which has an annular bevel 34 oppositely disposed to the bevel 31 of its related head 28. Seated between each disk 33 and head 28 directly upon the bevels 31 and 34 are correspondingly beveled portions of a friction tire 35, preferably rubber. It will now be noted that each disk 33 is slideable on the shaft 29, so that when a disk 33 is forced toward its related head 28 its related tire will be adjusted outwardly diametrically, while the opposite movement of the disk will permit its related tire to contract and thus reduce its diameter. The aforesaid movement of each disk 33 toward the related head 28 for the purpose of enlarging the diameter of the related tire 35 is accomplished by the manipulation of an adjusting nut 36 threaded on the shaft 29. During the reciprocation of the bed 12 each tire 35 engages a respective track 14 and directly rotates the roller E. This direct rotation or positive drive of the form inking roller by frictional contact of the tires 35 with the tracks 14 occurs both before and during the inking of a form by the roller and serves to prevent slurring of ink on the form upon initial contact of the roller therewith and during movement of the roller over the form.

The mechanism for inking the roller E is mounted on the frame portions 16 and 17 and comprises distributing rollers 37, 38, 39 which are journaled in and extend between the frame portions 16 and 17 and in such position that the form inking roller E can be moved into and out of contact with the distributing roller 37. Mounted on the frame portion 17 is an electric motor 40 whose shaft 41 extends transverse the axes of the distributing rollers and into a casing 42 and within said casing a worm 43 is fixed on the shaft and meshes with a worm wheel 44 fixed on the adjacent trunnion of the distributing roller 37. From this construction it will be apparent that upon operation of the motor 40, distributing roller 37 will be driven by the con-

nections between the same and the motor and that the rollers 38 and 39 will in turn be rotated by frictional contact with the roller 37.

In order to move the form inking roller into engagement with the roller 37 for re-inking, I provide on the side of the bed 12 remote from the rack 15 two plates 45 and 46 whose adjacent inner ends are spaced apart and shaped to provide oppositely disposed inclined surfaces 47 and 48 respectively, the upper edges of the plates being parallel to the bed 12. The arm 23 of the frame has a downward angular extension 49 and the free end of this extension carries a roller or cam follower 50 which, during each complete linear movement of the bed 12, cooperates with the surfaces 47 and 48 and with the upper edges of the plates 45 and 46 to move and hold the roller E in contact with the roller 37, so that said roller E is inked from the roller 37 at both the beginning and end of each printing stroke of the bed 12. In other words through the instrumentality of the structure just described, during normal operation of the press, the roller E and the form to be printed or proofed are both inked twice prior to an impression being taken from the form. It will of course be understood that when a form is applied to the bed it will lie between the inner ends of the plates 45 and 46, so that during both strokes of the bed 12 the roller E will be moved by gravity into inking engagement with the form and remain in such engagement until the roller 50 coacts with one or the other inclined surfaces 47 or 48, at which time it will be elevated into contact with the roller 37 and held in such contact by the upper edge of one of the plates 47 or 48 until the particular stroke of the bed 12 is completed and also until a predetermined portion of the succeeding stroke of the bed is also completed. It will thus be apparent that when the roller E is inking a form it is out of contact with all other rollers.

Another important feature of my invention resides in the relation of the circumference length of the form inking roller E to the printing length of the bed. In my present invention I make the circumference length of the form printing roller E at least equal to the printing length of the bed, so that during each inking of a form no part of the circumference of the roller E will engage the form twice with resulting enhancement of uniform distribution of ink on the form and the prevention of pale portions after the first revolution of small form rollers commonly used.

I claim:

1. In a printing press, an impression cylinder, a reciprocating form carrying bed one movement of which is a printing stroke and the other a non-printing stroke, a form inking roller, inking means into and out of con-

tact with which the form inking roller is movable, and means automatically operable at the end of each stroke of the bed to move the form inking roller from form inking position into contact with said inking means.

2. In a printing press, an impression cylinder, a form carrying bed having relative printing and non-printing movement with respect to the cylinder, a form inking roller, inking means into and out of contact with which the form inking roller is movable, and means automatically operable at the end of both the relative printing and non-printing movements of the bed to move the form inking roller from form inking position into contact with said inking means.

3. In a printing press, an impression cylinder, a reciprocating form carrying bed one movement of which is a printing stroke and the other a non-printing stroke, a form inking roller, inking means into and out of contact with which the form inking roller is movable, and cam means between the inking roller and bed operable at the end of each stroke of the bed to move the form inking roller from form inking position into contact with said inking means.

4. In a printing press, an impression cylinder, a reciprocating form carrying bed one movement of which is a printing stroke and the other a non-printing stroke, an inking device, a swinging frame, a form inking roller carried by the frame and shiftable in response to the movement of the frame into and out of contact with the inking device, spaced cams on the bed, and a cam follower on the frame cooperating with one of said cams at the end of one stroke of the bed and the other cam at the end of the other stroke of the bed to swing the frame and thereby move the form inking roller into contact with the inking device at the end of each stroke of the bed.

In testimony whereof I hereunto affix my
45 signature.

HENRY R. TROTTER.
